UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

ELECTRIC HEATER.

1,388,270.

Specification of Letters Patent. Patented Aug. 23, 1921.

Original application filed February 21, 1918, Serial No. 218,402. Divided and this application filed May 31, 1918. Serial No. 237,423.

To all whom it may concern:

Be it known that we, FRANK KUHN and JAY A. HAND, citizens of the United States of America, residing at Detroit, in the county of Wayne and State of Michigan, have invented certain new and useful Improvements in Electric Heaters, of which the following is a specification, reference being had therein to the accompanying

10 drawings.

The invention relates to electric heaters and more particularly to electric cookers of that type designed for use with chafing dishes, for toasting, broiling, etc. This application is a division of our prior application Serial No. 218,402, filed February 21, 1918, for an electric cooker.

It is necessary in the manufacture of heaters to provide units of different resistances and to correspond to the different voltages of the electric service in different places. As it is also necessary to mark the voltage on the heater in an exposed place where it can be easily read, it is customary 25 to place this marking on the outer casing or frame, which necessitates the carrying in stock of a large number of these frames which are mechanically of the same construction but are differently marked. We 30 have avoided this difficulty by placing the marking plate upon the detachable heating unit and exposing the markings to view through a window in the frame. Other objects of the invention reside in the novel 35 arrangements and combinations of parts as more fully hereinafter set forth.

In the drawings:

Figure 1 is a perspective view of the casing with the heating unit removed; 40 Fig. 2 is a perspective view of the heating unit detached;

Fig. 3 is a cross-section through a portion of the casing with the heating unit in place.

A is a base, preferably formed of pressed 45 sheet metal, having a flat top and depending side flange and which as shown is of polygonal form. B is an annulus which is supported above the base A by side members C. The latter are preferably formed 50 of pressed sheet metal and are slotted transversely to form racks for holding utensils below the ring. As specifically shown, the members C are provided with a series of slots D leaving uncut marginal portions at

opposite sides and these side portions are 55 crimped at E to form entrance grooves into the slots. There are also provided handles F which are attached to the members C by shank portions G struck out therefrom.

The heating unit H is of a form to fit 60 within the annulus B and to avoid over-heating the connector, the terminals of the unit are extended downward to a point adjacent to the base. To support these terminals a sheet metal member I is secured 65 at its upper end to the periphery of the unit and is extended downward therefrom, terminating in an outwardly-extending flange I'. On the downwardly-extending portion is mounted an insulator block J, 70 and secured upon this block are terminal bars K which extend upward and inward through slots K' in the member I. The lower ends of said terminal bars have attached thereto the outwardly-projecting 75 contact pins K² for engaging with the plug of the connector. The terminal connections just described are housed and protected by a casing L which is secured to the annulus B and extends downward adjacent to the 80 base, being fashioned to form in connection with the flange I' an outwardly-opening socket for receiving the plug. The construction is such that the heating unit may be engaged with or disengaged from the 85 casing by sliding it beneath the annulus B, inserting the member I into the housing L and then raising the unit into engagement with said annulus, where it is held from disengagement by securing means M. 90

The housing L has the window L' formed therein and the marking plate J' is mounted upon the insulator block J where it serves in addition to its function of a marking plate as a clamping plate for the terminal bars K. The plate is secured by screws J² and an insulator lining J³ of mica or other suitable material is placed between the plate and the conductors. 95

With the construction as described the 100 heating units, the specific construction of which forms no part of the present invention, may be formed of various resistances but mechanically of the same structure. Each unit is properly marked upon the 105 plate J' and the units are exchangeably engageable with the stand or frame member. Thus in assembling a heater for any

particular voltage it is only necessary to select the proper unit and to place the same in engagement with the stand or frame by sliding the terminals into the housing L and the unit proper into the annulus B, securing it by the pins M. When thus assembled, the voltage and other markings required are prominently displayed through the window L' so as to identify the heater.

10 It is also possible to quickly exchange the units when desired, so that it is only necessary to carry a limited number in stock.

What we claim as our invention, is:

1. In an electric heater, the combination 15 with a frame, of a heating unit detachably engageable with said frame, terminals for said unit projecting therefrom, a housing for said terminals secured to said frame, a marking plate for said unit secured to the

terminal portion thereof, and a window in 20 said housing through which the markings on said plate are displayed when said heating unit is in engagement with said frame.

2. In an electric heater, the combination 25 with a base, of an annulus supported thereabove, a heating unit detachably engageable with said annulus, terminals on said unit extending downward and outward therefrom, a marking plate for said unit secured to the terminal portion thereof, and 30 a housing for said terminals having a window therein for displaying the markings on said marking plate when said heating unit is in engagement with said annulus.

In testimony whereof we affix our signatures.

FRANK KUHN.
JAY A. HAND.
